UNITED STATES PATENT OFFICE.

JOSEPH CATLOW, OF PROVIDENCE, RHODE ISLAND, ASSIGNOR TO MANUEL F. WILLIAMS, OF PROVIDENCE, RHODE ISLAND.

DESIGN FOR A BUCKLE OR BROOCH PLATE.

SPECIFICATION forming part of Design No. 36,248, dated March 24, 1903.

Application filed January 12, 1903. Serial No. 138,769. Term of patent 3½ years

To all whom it may concern:

Be it known that I, JOSEPH CATLOW, a resident of Providence, in the county of Providence and State of Rhode Island, have invented and produced a new, original, and ornamental Design for Buckle or Brooch Plates; and I do hereby declare that the following is a full, clear, and exact description thereof, reference being had to the accompanying drawing, and to the letters of reference marked thereon, which forms a part of this specification.

My invention consists of an ornamental design for a buckle or brooch plate, the same consisting of the representation of a "fencing girl," and, as shown in the drawing, the leading or material features of my design are a girl dressed in a short skirt, standing on her left foot A, with the right leg B crossed be-

hind the left C, the left arm D hanging by 20 the side, the right hand E grasping a sword or foil F by the hilt, the point of which sword extends downward and rests on the toe of the left foot A. Over the left breast, at G, is the representation of a heart. This figure is 25 shown as standing before an oval border R.

Having described my invention, what I claim as new, and desire to secure by Letters Patent, is—

The ornamental design for a buckle or 30 brooch plate as herein shown and described.

In testimony whereof I have signed my name to this specification in the presence of two subscribing witnesses.

JOSEPH CATLOW.
